UNITED STATES PATENT OFFICE.

ROBERT J. HODGE, OF WEST HAVEN, CONNECTICUT, ASSIGNOR TO THE AMERICAN BUCKLE CO., OF WEST HAVEN, CONNECTICUT, A CORPORATION.

SLIDE BUCKLE.

Application filed April 28, 1927. Serial No. 187,285.

My invention relates to an improvement in slide-buckles, and more particularly to that class of slide-buckles primarily designed for use on the shoulder-straps of overalls, the object being to produce, at a low cost for manufacture, an attractive, convenient, effective and rugged buckle of the type described.

With these ends in view, my invention consists in a slide-buckle having certain details of construction as will be hereinafter described and pointed out in the claims.

In the accompanying drawings:

Fig. 1 is a view in front elevation of a slide-buckle embodying my invention;

Fig. 2 is an underside view thereof;

Fig. 3 is a view thereof in longitudinal section on the line 3—3 of Fig. 1; and

Fig. 4 is a view thereof in transverse section on the line 4—4 of Fig. 1.

In carrying out my invention, as herein shown, a piece of round wire of suitable length is bent to form a substantially-rectangular frame having parallel upper and lower bars 5 and 6 and two parallel end-bars 7 and 8. The ends of the wire forming the frame meet midway the length of the lower bar 6, where they are welded to form a joint 9 which, on account of the welding, is harder than the remainder of the buckle-frame and forms a fillet-like, annular projection upon the surface of the said lower bar. The upper bar 5 is flattened in the plane of the frame substantially throughout its length, so as to form a long, flat display-surface 10 having a long, straight, inwardly-extending edge 11 and a corresponding, long, straight, outwardly-extending edge 12, the said edges 11 and 12 respectively extending in the plane of the buckle-frame beyond the inner and outer surfaces of the ends of the wire forming the said upper bar. The said display-surface 10 provides ample space for the stamping upon it of the name of the maker of the buckle or the jobber thereof, or for a trade-name, or other descriptive or ornamental material, while the edge 11 contacts throughout its length with the overall strap (not shown) and by sharply deflecting it under the bar assists in holding it in place. The slide 13 aforesaid has its ends bent to form eyes 14 encircling the parallel end-bars 7 and 8 of the frame loosely enough to permit it to slide thereupon and have a slight rocking movement with respect to the plane

of the frame. As shown, the wire of which the said slide-bar 13 is made is rectangular in cross-section, though it may be of round or other cross-section, if preferred. As shown, it is a plain bar, but if desired it may be struck up to form teeth or it may be roughened to heighten its gripping effect. If desired, the flattening of the upper bar 5, as at 10, may be done without disturbing the outer face of the wire, in which case the long, straight, outwardly-projecting edge 12 would not appear and the surface 10 would be correspondingly narrower.

The lower bar 6 is symmetrically flattened in the plane of the frame on either side of the fillet-like projection 9, so as to produce two flat faces 15 corresponding in length and located substantially opposite the end-portions of the long, flattened display-surface 10 of the complementary upper bar 5. The said flat faces 15 provide straight, strap-gripping edges 16 extending into the buckle-frame in the plane thereof and also straight edges 17 extending outwardly beyond the outer surfaces of the ends of the bar, but, if preferred, the bar may be flattened so as not to disturb the outer face of the wire forming the same. The flat faces 15 may, also, if desired, carry stamped, descriptive lettering or ornamentation.

As shown, the slide-bar 13 is undulated so as to form a high-point 18 registering with the fillet-like projection 9 and with oppositely-extending high-points 19 registering with the central portions of the flattened faces 16 and with corresponding points on the long, flattened display-surface 10.

The flattening of the parallel upper and lower bars 5 and 6 not only provides strap-deflecting and gripping edges, as described, but stabilizes the buckle upon the overall-strap and enhances its appearance.

The buckle shown and described is preferably applied to an overall-strap so that its upper bar 5 will be uppermost and its lower bar 6 lowermost, but this is not imperative, since it will function to hold the overall-strap if reversed, in position. The user is not, therefore, obliged to stop and consider whether one side is to be the uppermost or the other, but, of course, it is preferably applied so that the bar 5 is uppermost, since that carries the display-surface 10.

I am aware that buckles of the type having tongues for penetrating the fabric have

been provided with round wire frames, flattened for the pointed ends of the tongues to bear upon. I do not, therefore, broadly claim a buckle made of wire and in part flattened, but only a slide-buckle frame made of wire and flattened for the two-fold purpose of co-acting with a slide-bar in gripping a strap and for the purpose of providing a display-surface.

10 I claim:

1. A slide-buckle, having a substantially-rectangular one-piece wire-frame, comprising parallel upper and lower bars and parallel end-bars, and a slide-bar having its ends slidably mounted upon the end-bars of the frame, the upper bar of which is flattened substantially throughout its length in the plane of the frame, so as to provide a display-surface, and the lower bar of which is adapted to co-act with the slide-bar in gripping the webbing.

2. A slide-buckle, having a substantially-rectangular one-piece wire-frame, comprising parallel upper and lower bars and parallel end-bars, and a slide-bar having its ends slidably mounted upon the end-bars of the frame, the upper bar of the frame being flattened substantially throughout its length in the plane of the frame to provide a display-surface, and the lower bar of the frame being flattened in the plane of the frame, for co-action with the said slide-bar.

3. A slide-buckle, having a substantially-rectangular one-piece wire-frame, comprising parallel upper and lower bars and parallel end-bars, and a slide-bar having its ends slidably mounted upon the end-bars of the frame, which is made from a single piece of wire, the ends whereof are abutted and welded together midway the length of its lower bar, which is symmetrically flat-

tened in the plane of the frame on opposite sides of the said weld for co-action with the said slide-bar, the upper bar of the frame being flattened substantially throughout its length in the plane of the frame to provide a display-surface.

4. A slide-buckle, having a substantially-rectangular wire-frame having parallel upper and lower side-bars and parallel end-bars, and a wire slide-bar of substantially rectangular cross-section, having its ends bent over to loosely embrace the said end-bars upon which the said slide has sliding and rocking movement, the upper bar of the frame being flattened substantially throughout its length to form a display-surface, and the lower bar of the frame being symmetrically flattened on opposite sides of its center to form gripping-surfaces for co-action with the slide-bar.

5. A slide-buckle, having a substantially-rectangular one-piece wire-frame having parallel upper and lower bars and parallel end-bars, the ends of the wire being abutted and welded midway the length of the lower bar, and a wire slide-bar slidably mounted upon the end-bars of the frame and of undulating form, the upper bar of the frame being flattened in the plane of the frame substantially throughout the length thereof to provide a display-surface, and the lower bar of the frame being symmetrically flattened in the plane of the frame on opposite sides of the weld thereof to provide gripping-edges, and the undulations of the said slide-bar registering with the said flattened portions of the said lower bar of the frame.

In testimony whereof, I have signed this specification.

ROBERT J. HODGE.
